UNITED STATES PATENT OFFICE.

NELS T. NELSON, OF ATTLEBORO, MASSACHUSETTS, ASSIGNOR TO J. F. STURDY'S SONS CO., OF ATTLEBORO FALLS, MASSACHUSETTS, A CORPORATION OF MASSACHUSETTS.

BUCKLE.

Application filed December 16, 1922. Serial No. 607,408.

To all whom it may concern:

Be it known that I, NELS T. NELSON, a citizen of the United States, residing at Attleboro, in the county of Bristol and State 5 of Massachusetts, have invented certain new and useful Improvements in Buckles, of which the following is a specification.

This invention relates to an improved construction of buckle more particularly 10 adapted for adjustably connecting together the ends of bands or straps for wrist watches and the like, but which may be employed for any other purpose for which it is adapted; and the object of this invention 15 is to provide a readily-removable bar for the buckle on which the buckle-tongue is pivotally mounted, whereby the bar may be removed to receive the loop formed at the end of the strap, and to also facilitate the removal 20 of this strap portion when worn to be replaced by a fresh one.

With these and other objects in view, the invention consists of certain novel features of construction, as will be more fully described, and particularly pointed out in the appended claims.

In the accompanying drawings,

Figure 1 is a perspective view showing the back of a watch and the strap or band as 30 attached to the watch with its free ends adjustably connected together by means of my improved buckle.

Figure 2 is a front view of my improved buckle showing a portion of a strap in dotted lines as applied to the cross-bar thereof.

Figure 3 is an enlarged sectional elevation of my improved cross-bar.

Figure 4 is an end section of my improved bar on line 4-4 of Figure 3 showing the 40 tongue as mounted thereon.

Figure 5 is a perspective view of the center spindle of my bar removed.

Figure 6 is a perspective view of one of the end bushings of the bar removed.

Figure 7 is a perspective view of the outer shell of the bar.

Figure 8 is a side elevation of the gripping spindle retaining coil spring adapted to be mounted in the space in the bar formed 50 to receive it.

Figure 9 is a modification showing the ends of the shell turned in to form bearings for the center spindle to take the place of the bushings.

It is found in practice of advantage to 55 provide a buckle of the type described, having a tongue to enter holes in the strap or band for adjustably securing the ends of the band together, and it is also found of advantage to provide a removable cross-bar 60 in this buckle frame adapted to be readily removed to be passed through the loop or eye formed in one end of the strap to receive it, whereby the loop may be formed in the strap at the factory ready to be attached to the buckle without being obliged to sew or otherwise fasten the folded back and to secure the strap end after having been applied to the buckle; and the following is a detailed description of one means 65 by which the removability of the bar of the buckle frame may be accomplished:—

With reference to the drawings, 10 and 11 designate portions of a strap or band the one herein shown being a wrist band worn more 70 particularly by a man for attaching a time-piece to his arm. To one of these ends is secured a buckle 12 which is preferably made in the form of a U-shaped frame having an eye or loop 13 at each of its ends and between these ends I have mounted a cross-bar 14 which is formed with an outer shell 15 which is usually made of thin precious metal and of a length to fit between the side arms 75 of the U-shaped buckle frame. 80

Into each of the opposite ends of this shell, I force a short bushing 16 having a central hole 17 and a central spindle 18 is mounted to extend through this shell and through the openings in these bushings with 85 its ends projecting beyond those of the shell to receive their bearings in the eyes of the frame ends 13. 90

In order to frictionally retain this spindle in adjusted position in the sleeve, I have 95 mounted a coil spring 19 in the space between the inner ends of the bushing, the same having an internal diameter of a size to grip the external surface of the spindle so that when the spindle is forced through the 100 coil it is gripped and firmly held by all of the multiplicity of its convolutions and as the ends of the spring abut against the opposite inner ends of the bushings the spindle is held against endways movement except 105 when considerable force is brought to bear endways upon it.

In some instances I may, if desired, corru-

gate or roughen that portion of the surface of the spindle, engaged by the coil, as illustrated at 20 in Figure 5, whereby the coil will more firmly grip the spindle and prevent relative endways movement of the same when positioned in its shell.

I do not wish to be restricted to the inserting of separate and independent bushing members into the ends of the shell as in some cases the stock at the ends of the shell may be turned inwardly to take the place of the bushings and form bearings for the center spindle.

The buckle tongue 21 is provided with an eye 22 through which the cross-bar is freely passed, the tongue being adapted to enter any of the holes 23 in the strap to adjust the same about the wrist of the wearer.

In applying the strap to my improved buckle, the member 11 of the strap is preferably provided with a loop 24 when made at the factory, as shown in Figure 1, by folding the extremity thereof back upon itself and cementing, riveting or sewing this folded portion to the body of the strap, and an opening or slit 25 is formed to receive the tongue 21.

In order to attach the strap to my improved buckle, it is only necessary to force the spindle 18 out, remove the bar and insert it with its tongue into the loop of the strap, the latter may then be placed in line with the eyes in the ends of the frame and the spindle forced through the shell, the spindle being firmly retained in its operating position by the grip of the coil until it is desired to again remove it to replace the strap when worn by a fresh one.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. A buckle comprising a frame adapted to receive a spindle, a cross-bar mounted in said frame, a readily-removable center bearing spindle therein connecting said cross-bar and frame, a strap-engaging tongue mounted to swing on said bar, and an independent resilient gripping member in said bar for frictionally retaining said spindle in said bar.

2. A buckle comprising a frame, a removable spindle supported in said frame, a cross bar having an outer shell, and bushings in said shell pivotally supported on said spindle, and a resilient gripper engaging said spindle to frictionally retain it in set position in said shell.

3. A buckle comprising a frame having bearings in its ends, a cross-bar mounted in said frame and having an outer shell, bearings at the ends of said shell forming a chamber between them, a center spindle extending through the chamber in said shell and supported in said bearings, the ends of said spindle extending beyond those of said shell and received in the bearings in said frame ends, and means for frictionally retaining said spindle in said shell.

4. A buckle comprising a frame having bearings in its ends, a cross-bar mounted in said frame and having an outer shell, bearings at the ends of said shell forming a chamber between them, a center spindle extending through the chamber in said shell and supported in said bearings, the ends of said spindle extending beyond those of said shell and received in the bearings in said frame ends, and a frictional member in the chamber in said shell for retaining said spindle against endways movement therein.

5. A buckle comprising a frame, a cross-bar rotatably mounted in said frame and having an outer shell, bearings in the ends of said shell, a center spindle supported by said bearings in said shell and having extended ends supported in said frame, and a coil spring located in the space between said bearings and arranged to grip said spindle and retain it in position.

6. A buckle comprising a frame, a cross-bar rotatably mounted in said frame and having an outer shell, bearings in the ends of said shell, a center spindle supported by said bearings in said shell and having extended ends supported in said frame, and a coil spring located in the space between said bearings with its ends abutting against said bearings, the coils of said spring gripping said spindle to frictionally retain it against endways movement and arranged to grip said spindle and retain it in adjusted position.

In testimony whereof I affix my signature.

NELS T. NELSON.
